UNITED STATES PATENT OFFICE.

OLIVER C. DENNIS, OF WILMETTE, ILLINOIS.

CIGAR LIGHTER.

Application filed April 7, 1926. Serial No. 100,219.

This invention relates to electric cigar lighters.

One object of the invention is to provide a lighter of this type which is simple in construction and which is adapted to be produced in large quantities at a very low cost.

Another object of the invention is to provide a lighter of this type which is composed of comparatively few parts and which may be quickly and readily assembled for use.

Other objects of the invention will appear from the detail description.

The invention consists in the several novel features hereinafter set forth and more particularly defined by claims at the conclusion hereof.

In the drawings: Fig. 1 is a perspective of a portion of the panel of a vehicle on which the instrument and accessories are usually mounted, the invention being shown thereon. Fig. 2 is a side elevation of the lighter. Fig. 3 is a perspective of the unitary support which is adapted to fit into the casing. Fig. 4 is a longitudinal section. Fig. 5 is a view, showing the several parts in the course of assembling. Fig. 6 is a section on line 6—6 of Fig. 4. Fig. 7 is a plan.

The invention is exemplified in a device comprising a tubular sheet metal casing 10 which has one of its ends open and its other end 11 turned inwardly to form a flange which has a hole 12 therein for the conductor wires. A member 14 of suitable insulating material, such as lava, and formed of a single piece, is adapted to be inserted into the tubular casing 10 and to support, in properly connected relation, the resistance element and the switch for controlling the circuit through said element. Supporting member 14 is adapted to be inserted through the open end of the casing 10 and comprises a cylindrical head 15, which fits into and closes the open end of the casing, and an integral shank 16, which is adapted to extend into the casing and is narrowed so as to leave spaces in the casing for the switch and the conductor wires. A countersink or recess 17 is formed in the outer face of head 15 and a convolute coil of resistance wire 18 is held in said recess. One terminal of said element is extended through the head and shank of support 14, at 19, and electrically connected to a hollow rivet 20 which extends transversely through and is

fixed in the shank 16 of the support 14. The other end of resistance element 18 is connected by a portion 21 which extends through the head 15 to a hollow rivet 22 which extends through and is fastened to the shank 16 above the rivet 20. One of the conductor wires 23 has its end fixed under one of the flanges of the rivet 20 and the other conductor wire 24 has one of its ends riveted under one of the flanges of a hollow rivet 25 which extends through the shank 16 and through one end of a resilient switch strip 26. The other end 27 of the switch strip is normally spaced from the rivet 22 and is adapted to be flexed into contact with said rivet to complete the electric circuit for the operation of the resistance element. The lower end 28 of the strip 26 is bent under the lower end of the shank 16 to lock the strip against rotation.

A button 29 is held in a hole 30 formed in one side of the casing 10 and is provided at its inner end with an enlargement or head 31 which causes the button to be retained with the casing. Switch strip 26 presses the button 29 outwardly so that no separate spring is necessary for retracting the button. A cross rib 32 is formed on one of the side faces of shank 16 adjacent the inner end of the button 31 to serve as an abutment for resilient strip 26 which will prevent excessive pressure of the button 29 from distorting the resilient strip 26.

The conductors 23 and 24 extend through a cup-shaped washer 34 which is adapted to be inserted through the open end of casing 10 and slipped downwardly into position to close the hole 12 in the casing. The conductor wires are threaded through an opening 35 in the washer 34, and the latter is preferably formed of insulating material. The casing is formed with an annular out-turned bead 36 which serves as a stop to prevent the casing from slipping from the fingers when the lighter is being used. An annular groove 37 is formed in the outer periphery of the head 15, so that by indenting the casing at one point, as at 38, to enter said groove, the supporting member 14 will be retained against axial movement in the casing 10. A longitudinal groove 39 is formed in the outer periphery of head 15 between groove 37 and the lower end of the head, and the casing 10 is indented, as at 40, to enter said groove to secure the member 14 against rotation in the casing, so that the

switch strip 26 will remain in engagement with the button 29.

In assembling the device, the resistance element is placed in position in the member 14, its terminal 21 is extended under one of the flanges of the rivet 22, and the latter is then pressed into position; the other end 19 of the resistance element and the terminal of conductor 23 are secured in connected relation by fastening the rivet 20 in the shank 16; the switch strip 26 and the terminal of conductor 24 are then fixed to the member 14 by fastening said rivet in the shank 16; the member 14, with the resistance element, switch strip and conductors connected thereto, is then inserted into the casing 10, button 29 being held in opening 30 and the switch-strip being aligned with the button during insertion, so that the button will be held in the casing by said strip. The casing is then indented at 38 and 40, and thereupon the entire device will be assembled.

The lighter is adapted to be held by a simple form of clip 41 which may be secured to the dashboard or any other suitable support. To operate the lighter, it is only necessary to press the button 29 which will complete the circuit through the resistance element 18. When the button is released, the switch 26 will open and the circuit will be broken.

The invention exemplifies a cigar lighter, which is simple in construction; in which all of the electrical connections are mounted on, and made to, a unitary member which is adapted to be inserted into a casing after the connections have been made; in which the tubular casing may be formed of sheet metal; in which the resilient switch-member holds the operating button in place and retracts it; in which the support is provided with an abutment for preventing distortion of the spring; in which the electrical connections are made by means of rivets fastened in the supporting member, and which makes it possible to easily assemble the device and at a low cost.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a cigar lighter, the combination of a tubular casing having one of its ends open, a supporting member of non-conducting material adapted to be inserted into and secured in the casing, comprising a head fitting in the open end of the casing, and a reduced shank, a resistance element mounted on the outer end of the head, rivets extending through the shank and to which the terminals of the resistance element are respectively connected, flexible conductors ex-

tending through and into the casing, one of which is connected to one of the rivets, a spring switch mounted on the shank, connected to the other conductor and adapted to contact with one of the rivets, and a button 70 movable in the casing to shift the strip to close the circuit through the resistance element.

2. In a cigar lighter, the combination of a tubular casing having one of its ends open, 75 a supporting member of non-conducting material adapted to be inserted into and secured in the casing and comprising a head fitting in and closing the open end of the casing, and an integral reduced shank, a resistance element mounted on the outer end of the head, a pair of rivets extending through the shank and to which the terminals of the resistance element are respectively connected, conductors extending through 80 the other end of the casing, one of which is connected to one of the rivets, a spring switch strip mounted on the shank so as to be movable into contact with the rivet to which said conductor is connected, a rivet 90 for securing the switch strip to the shank and to which the other conductor is connected, and a button movably held in the wall of the casing to operate the strip to close the circuit through the resistance element. 95

3. In a cigar lighter, the combination of a tubular casing having one of its ends open, a supporting member of non-conducting material adapted to be inserted into and secured in the casing and comprising a head 100 fitting in and closing the open end of the casing, and an integral shank, a pair of resistance elements mounted at the outer end of the head, rivets extending through the shank and to which the terminals of the 105 resistance elements are respectively connected, conductors extending through and into the other end of the casing, one of which is connected to one of the rivets, a switch strip mounted on the shank and adapted to contact with the rivet to which said conductor is connected and to which the other conductor is connected, and a button 110 slidably in the wall of the casing to operate the strip to close the circuit through the resistance elements, and insertable into the wall from the inside of the casing and having a stop on the inside of the casing, the strip being adapted to hold the button in said wall. 115

4. In a cigar lighter, the combination of a 120 tubular casing having one of its ends open, a supporting member of non-conducting material adapted to be inserted into and secured in the casing and comprising a head fitting in and closing the open end of the casing, and an integral shank, a resistance element mounted at the outer end of the head, a pair of rivets extending through the shank and to which the terminals of the 125 resistance element are respectively connected, 130

- conductors extending through the casing, one of which is connected to one of the rivets, a switch strip to which the other conductor is connected, mounted on the shank 5 to contact with the rivet to which said conductor is connected, an integral projecting stop rib on the shank to prevent excessive movement of the strip, and a button movable in the casing to operate the strip to close the 10 circuit through the resistance element.
5. In a cigar lighter, the combination of a tubular casing having one of its ends open, a supporting member of non-conducting material adapted to be inserted into and se- 15 cured in the casing and comprising a head fitting in and closing the open end of the casing, and a shank, a resistance element mounted at the outer end of the head, an annular groove in the head, an indentation 20 in the casing extending into said groove to hold the head in the casing, rivets extending through the shank and to which the terminals of the resistance element are connected, conductors extending through and to which the terminals of the resistance element are connected, conductors extending 25 into the casing, one of which is connected to one of the rivets, a resilient switch strip mounted on the shank to contact with one of the rivets, and a button movable in the casing and adapted to operate the strip to
- close the circuit through the resistance ele- 30 ment.
6. In a cigar lighter, the combination of a tubular casing having one of its ends open, a supporting member of non-conducting ma- 35 terial adapted to be inserted into and se- cured in the casing and comprising a head fitting in and closing the open end of the casing, and a shank, a resistance element mounted at the outer end of the head, an annular groove in the head, an indentation 40 in the casing extending into said groove to hold the head in the casing, a horizontal groove in the periphery of the head, an in- 45 dentation in the casing extending into said longitudinal groove to hold the head against rotation, rivets extending through the shank and to which the terminals of the resistance element are connected, conductors extend- 50 ing through and into the other end of the casing, one of which is connected to one of the rivets, a switch strip mounted on the shank and adapted to contact with one of the rivets, and a button movable in the casing to operate the strip to close the cir- 55 cuit through the resistance element.

Signed at Chicago, Illinois, this 2nd day of April, 1926.

OLIVER C. DENNIS.
